UNITED STATES PATENT OFFICE.

HENRY KINGSFORD HARRIS, OF WESTMINSTER, LONDON, ENGLAND.
RECORDING APPARATUS FOR USE IN CONNECTION WITH ADVERTISING DEVICES AND
THE LIKE.

1,291,863.

Specification of Letters Patent. Patented Jan. 21, 1919.

Application filed June 7, 1915. Serial No. 32,631.

To all whom it may concern:

Be it known that I, HENRY KINGSFORD HARRIS, a subject of the King of Great Britain and Ireland, residing at 96 Victoria street, Westminster, in the county of London, England, have invented certain new and useful Improvements in Recording Apparatus for Use in Connection with Advertising Devices and the like; and I do hereby declare the following to be a full, clear, and exact description of the invention, such as will enable others skilled in the art to which it appertains to make and use the same.

15 This invention relates to an electrical recording mechanism which is more particularly applicable for use in connection with devices for exhibiting public announcements, advertisements or the like, in which the mechanism for setting the bands, cards, flaps or other means carrying or forming letters or other symbols to be exhibited are set by electrical impulses transmitted from a sending station.

25 The object of the apparatus is to enable the various settings of the advertising or other apparatus at the exhibiting station to be recorded, thus affording a check upon the operator, especially in the case of hand-transmitted impulses and also rendering it possible to preserve permanent details of advertisements or other announcements exhibited.

35 In order that the said invention may be clearly understood, I will describe one representative form of the apparatus with reference to the accompanying drawings, in which—

40 Figure 1 is a front elevation of the apparatus;

Fig. 2 is a rear elevation of a part of the apparatus with the back of the casing removed.

45 Figs. 3 and 4 show details hereinafter referred to.

Fig. 5 shows a diagram of connections of an advertising system of the kind previously referred to, illustrating one method of connecting up the magnets of the recorder.

50 Referring to Figs. 1 to 3, 1 is an escape-
ment and ratchet provided with a spring barrel 2, the spring of which is tending to turn the ratchet wheel in the direction of the arrow. The axle of the wheel 1 passes
55 through the casing and has mounted there-

on in such a manner that its position can be adjusted a type wheel 3. The type on the wheel 3 runs in contact with a rotary inking pad 4 carried upon a detachable arm 5 kept pressed against the type wheel by means of a spring 6. The arm 5 is shown detached at Fig. 4 in plan; it will be seen that a shield 5¹ is provided which comes around the lower part of the inking pad 4 for the purpose hereafter specified. 7 is a feeding lever and 8 are the roughened feeding rollers, the upper one being mounted upon an arm 9, the axle of which passes into the casing and has mounted thereon a snail-like catch 10 upon which the end of a flat spring 11 presses. In this manner the upper feeding roller 8 is pressed tightly into contact with the lower roller 7, this latter roller 8 being caused to rotate periodically with the feeding mechanism in the manner hereinafter described.

12 is a wheel carrying a roll of tape 13 which passes down around the guide roller 14 beneath the metallic shield of the inking roller 4 over the upper portion of the feeding lever 7 between upstanding guides, beneath a pin 15 and thence between the feeding rollers 8 and on to the strip 16. 17 is an electro-magnet which is arranged to be constantly in the impulse circuit of every unit as hereinafter explained with reference to the diagram of connections. Each time an impulse passes, the electromagnet 17 causes the pawl 18 in connection with its armature 19 to rock upward and move the ratchet wheel 1 around through the distance of one tooth.

At the first operation of the pawl, beginning any fresh series, the carrier of the pawl 18 comes into contact with the projecting end of a screw 20. The screw 20 is mounted at the end of the arm of a rocking lever 21 pivoted to the casing; the other arm of which is also provided with a projecting screw 22, adapted when the lever is rocked up as previously explained to come into contact with an arm 23 and release a locking pawl 24 from engagement with the spring rotated ratchet wheel 1. 25 is a nose adjacent the projecting screw 22. This nose 25 when the preceding action has taken place comes out of contact with the lever 26 and allows another pawl 27 to engage with the teeth of the ratchet wheel 1 by means of a spring 28. Each time the electromagnet 27

is operated the pawl 18 rotates the ratchet wheel through one tooth, as previously explained and the ratchet wheel is prevented from turning back by means of a hooked pawl 27. When a series of impulses has been sent to any particular unit and the switch is just going to be changed over to the next unit the circuits are so arranged that the current to produce this effect 10 traverses another electromagnet 29 as hereinafter explained with reference to the diagram. The armature of this electromagnet is mounted upon a spindle 30 which projects through the casing and has mounted thereon a lever 31. 32 is a pin mounted some way along this lever which passes through a slot in the casing and is connected to a downwardly extending arm 33 of the arm 23, thus when the electromagnet 15 29 is again energized, the arm 31 is caused to rise which action causes the pawl 24 to engage with the ratchet wheel 1, at the same time this arm 23 forces up the bottom of the screw 22 and causes the projecting nose 20 thereof to force the retained pawl 26 from engagement with the teeth. On the outside of the casing this action has caused the screw 34 to press beneath the feeding piece 7 and lift it upward. This forces a 25 portion of the tape or paper into contact with the particular letter on the type wheel which has been brought into position by the movement of the ratchet wheel 1. When the current through the electromagnet 29 is 30 broken, the arm 31 drops. This causes the pawl 24 to be brought out of contact with the teeth of the ratchet wheel 1 and as now there is nothing holding the said ratchet wheel it turns around in the direction of the 35 arrow under the action of the spring in the spring barrel 2 until the damping projection 40 comes into contact with the adjustable stop 36 bringing the parts into position shown in Fig. 5 ready for starting. The 45 paper strip has been caused to travel by the previous action owing to a pin 31* projecting from the lever 31 into a slot in the casing and engaging in a tongue 37 at the end of the locking arm 39. The spindle of the 50 locking arm has connected thereto at the interior of the casing an arm 39 at the end of which is located a spring pawl 40 which engages with the ratchet wheel 41. 42 is a spring controlled pawl. The spindle 43 of 55 the ratchet wheel 41 extends through the casing and upon this projecting spindle the lower feeding wheel 8 is located. Consequently when the arm 31 is rocked upward the lower wheel 8 is rotated in the direction 60 of the arrow 44 and as the upper roller 8 is kept pressed tightly upon the lower roller and both rollers are serrated or roughened upon their rolling surfaces, the paper will be pulled between same. Upon 65 another series of impulses being sent the

printing wheel is again brought into a suitable position and when the selecting switch is operated the electromagnet 29 is again operated which prints a fresh letter or the like. In this way a complete record is kept 70 of the letters, signs or other characters set in the various units and in their exhibited sequence.

Referring to Fig. 5, a recorder is shown suitably connected to the circuit of one type 75 of hand-transmitting apparatus in which a number of contacts 48 are adapted to send electrical impulses over suitable lines to advertising units 45 each provided with a magnet 46. A switch 48 is provided controlled by 80 an electromagnet 47 of high resistance, for switching each unit 45 into circuit in succession, that is to say a unit is brought into circuit by a suitable impulse being sent to the magnet 47 causing the arm 48 to throw 85 the said unit into circuit and then a series of electrical impulses are sent to the magnet 46 of this unit which causes say a selector to be set into a certain position. This selector subsequently determines the position that a 90 band or the like bearing letters, numerals or other signs is to take up. The electro-magnet 17 of the recorder 50 is arranged in the circuit over which the electrical impulses are sent to set the selector and it will thus be 95 seen that each impulse will cause the ratchet wheel 1 to be moved by the pawl 18 through one tooth and as the characters on the printing wheel 3 are similar and in a similar order to those upon the advertising band or 100 the like, the printing wheel will be set so that the letter or the like in the printing position thereon is the same as that which will be set in the particular unit under consideration.

When the required number of impulses has been sent to the particular unit, as before stated, a current is sent through the electromagnet 47 which causes the switch arm 48 to be moved on to the next unit. In 105 the circuit over which this current flows the magnet 29 is arranged and as previously described when a current passes through this magnet the letter or the like on the printing wheel 3 which is for the time being in the 110 printing position, is printed, and then the locking pawls holding the ratchet wheel 1 are released causing the said ratchet wheel to turn back to its initial position under the action of the spring in the spring barrel 2 115 and at the same time the paper strip bearing the printed impression is moved onward or spaced, bringing a fresh portion into position for receiving the next impression.

From the foregoing description of the 120 general operation of the device, the following detailed statement of the operation will be readily understood.

The transmitter shown diagrammatically, by way of example, is a hand transmitter 125

of the dial type, the pointer handle 80 is pivoted at the center and has two conducting bridges with suitable spring brushes 81 connecting the respective studs and rings as described hereinafter.

The handle is set around to the desired letter, and the return movement is effected by a spring control with a fly governor, (not shown).

10 The instrument is so arranged that when the pointer handle is moved forward by hand for setting no contacts are made but as it returns under the influence of its spring control, it first sends the letter determining impulses to set the unit selector which is in the circuit and then sends the spacing impulse, and on coming to the rest position switches in the "rest" circuit and battery. I mean by the "rest" circuit a 15 circuit which is operative when the instrument is at rest, that is when no settings are being effected. Mounted on the case are the green and red signal lamps 59 and 58 and attached to the mechanism within is the 20 electromagnet in circuit with a red lamp which automatically locks the movement when the setting of the selector at the distant station is completed. The operation is as follows:

30 When the pointer hand of the transmitter is at rest, it connects by the spring plunger brushes 81 which it carries, contact studs 51 to 52 and 53, and the ring 55 to the stud 54. The effect of this is that the current 35 flows from the positive pole of the low voltage rest battery 71, to the stud 51 then through the insulated conductor on the arm to the studs 52 and 53. It passes from 53 through the green lamp 59 thence over the 40 line 60 to the first plate 62 on the selector at the exhibiting station, that is to the first jack or stud 62, through the selector brush arm 48 which rests upon it, when the selector is ready for resetting, to earth and 45 back through the earth to the contact ring 55, through the other insulated conductor on the pointer arm to the stud 54 and thence to the negative pole of the rest battery. This causes the green lamp 59 to be lighted so 50 that the operator knows he can reset. He therefore moves the pointer to the second stud 64 on the outer circle. This causes the brushes it carries to leave 52, 53, 54, and 51 and to make contact instead between the 55 inner ring 63 and the second stud 64 on the outer circle and between the second and third rings 55 and 66. The inner ring is connected to the positive pole of the hundred volt supply from the motor generator. This 60 is not shown, but it is in connection with the studs marked + and -. The current therefore passes from the inner ring 63 through the pointer arm to the second contact stud 64, thence through the spacing magnet 29 65 of the printer, through the line 61, through

the high resistance magnet 47 which moves the selector arm 48 to the second contact plate or jack, the current going from the magnet to earth and thence to the earth at the transmitting station, to the ring 55 70 through the pointer arm to the next outer ring 66 and so back to the motor generator. The effect of this has been to move the selector arm as described and space the paper in the printer as no type is in the printing 75 position. The pointer arm has returned to zero but does not now close any lamp circuit as the selector arm 48 has been moved and the operator now sets the pointer to the first letter he desires and allows it to turn. This 80 sends current from the positive pole of the generator by the inner ring 63 through the pointer arm to the outer contact studs 49 which are connected together and of which only a few are shown (that is the first three) 85 thence from 49 to the type wheel setting magnet 17 and thence to the line 60. As the pointer arm returns it makes and breaks a number of contacts according to the number of studs 49 it passes over. These current 90 impulses through the magnet 17 set the type wheel to the corresponding letter and passing on by the line 60 take the circuit through the selector magnet of the first unit 45, as it is on this one that the arm 48 rests, thence 95 it returns by the earth to the transmitting station and by the ring and pointer arm to the negative pole of the generator. The pointer arm as it returns, after sending the impulses by the contacts 49, passes over the 100 second stud 64 as before described. This sends an impulse through the magnet 29, printing the letter carried by the type wheel which was set in position by the last operation, and spacing the paper tape ready for 105 a new indication and returning the type wheel to zero. The same impulse operating the magnet 47 moves the unit switching arm 48 to the third contact. The operation is repeated until all the selectors in the units 45 110 have been set and the arm 48 is automatically moved on as before from the last unit contact jack to the last contact jack 70 which is connected to the line 61. This completes the circuit. When the pointer arm of the 115 transmitter comes to rest, the circuit is closed from the positive of the "rest" battery 71 through the stud 51, the pointer arm to the stud 52, through the locking magnet inside the transmitter (not shown but in 120 circuit with the red lamp 58, locking the pointer arm) through the red lamp 58 and the line 61 to the last contact jack 70 on the unit switching selector, through the arm 48 and thence to earth and back to the negative 125 pole of the rest battery 71 as before described. It should be noted that the magnet 47 being of high resistance is not affected by the low voltage rest current and prevents the current from going to earth that way as 130

it chooses the path of least resistance by the last jack 70 and arm 48. When the arm rests here, it also, by a plate it carries, closes the starting circuit of the motor, which sets the units in position by joining the two studs 73 and 72.

In the case shown, first of all the selectors 46 in the units 45 are all set into position for determining the position to be taken up by 10 the exhibiting bands or the like in the units and after this has been done, as just described, the contact arm of the unit switching selector, that is the arm 48, closes a circuit which causes a motor to drive all the 15 bands or the like, or a number of motors, where each unit has its own, for bringing the exhibiting members into position.

In the apparatus under consideration, the 20 type wheel when at zero, presents a blank to the tape, and therefore does not print and if the spacing magnet is operated it simply moves on the tape which has nothing impressed thereon.

It is to be observed that, by moving the 25 selector arm for selecting the units in succession, that is by moving on the arm 48 and when it is in position making the contact by means of the transmitter arm with the spacing contact stud at 64, no indication 30 is shown on the unit 45 corresponding to the stud in the unit switching selector and that if the arm 48 is thus caused to travel over any number of the studs or jacks, say 5, it follows that five units will be left blank, or 35 four if the arm starts from the jack 62.

The apparatus which has been described in detail is intended for use where impulses 40 for setting a directly fed band, selector or other device for bringing letters or other symbols into position or for determining the position into which such letters or symbols are to be brought, is employed.

Minor modifications of construction may be introduced without departing from the 45 principle of my present invention.

What I claim as my invention and desire to secure by Letters Patent of the United States of America is:—

1. The combination with a plurality of 50 electrically actuated display devices, of a recording device having a type bearing member, electro-magnetic means in circuit with one of said display devices for actuating the type bearing member to bring the latter into printing position, means for bringing the 55 series of display devices successively into circuit with said electro-magnet actuating device, said last named means comprising a switch, a series of contacts each having electrical connection with one of said display devices, and a magnet for moving said switch.

2. The combination with a plurality of 60 electrically actuated display devices, of a recording device having a type bearing mem-

ber, electro-magnetic means in circuit with one of said display devices for actuating the type bearing member to bring the latter into printing position, means for bringing the series of display devices successively into circuit with said electro-magnetic actuating device, said last named means comprising a switch arm, a series of contacts each having electrical connection with one of said display devices, a magnet for moving said switch arm, a magnet carried by the recording device in circuit with the switch actuating magnet, and means controlled by the recording device magnet for resetting the type bearing member to its original position. 80

3. The combination with a plurality of 85 electrically actuated display devices, of a recording device having a type bearing member, electro-magnetic means in circuit with one of said display devices for actuating the type bearing member to bring the latter into printing position, means for bringing the series of display devices successively into circuit with said electro-magnetic actuating device, said last named means comprising a 90 switch, a series of contacts each having electrical connection with one of said display devices, a magnet for moving said switch, a magnet carried by the recording device in circuit with the switch actuating magnet, 95 means controlled by the recording device magnet for causing the type bearing member to print a record, and means for resetting the type bearing member to its original position. 100

4. The combination with a plurality of 105 electrically actuated display devices, of a recording device having a type bearing member, electro-magnetic means in circuit with one of said display devices for actuating the type bearing member to bring the latter into printing position, means for bringing the series of display devices successively into circuit with said electro-magnetic actuating device, said last named means comprising a 110 switch, a series of contacts each having electrical connection with one of said display devices, a magnet for moving said switch, a magnet carried by the recording device in circuit with the switch actuating magnet, 115 means controlled by the recording device magnet for causing the type bearing member to record, a record carrier and means for causing the step by step movement of the record carrier for spacing the characters 120 of the record.

5. The combination with a plurality of 125 electrically actuated display devices, of a recording device having a type bearing member, electro-magnetic means in circuit with one of said display devices for actuating the type bearing member to bring the latter into printing position, means for bringing the series of display devices successively into circuit with said electro-magnetic actuating de- 130

vice, said last named means comprising a switch, a series of contacts each having electrical connection with one of said display devices, a magnet for moving said switch, 5 a magnet carried by the recording device in circuit with the switch actuating magnet, means controlled by the recording device magnet for causing the type bearing member to record, a record carrier, means for causing the step by step movement of the rec-

ord carrier for spacing the characters of the record, and means for resetting the type bearing member to its original position.

In testimony whereof I affix my signature in presence of two witnesses.

HENRY KINGSFORD HARRIS.
